WIRE STRAPPING TOOL

Herbert Embree, Hamilton, Ontario, Canada, assignor to Griplock, Inc., New York, N. Y., a corporation of Delaware

Application April 25, 1939, Serial No. 269,883

5 Claims. (Cl. 140—93)

This invention relates to a wire strapping tool designed for fastening wire straps or the like around packages. It is well adapted for use with straps such, for instance, as those shown in U. S. Patent to W. N. Lurcott No. 1,474,372, granted November 20, 1923, in which one end of the strap is coiled back on the body and the knot or gripping formation is made by inserting the other end of the strap through the said coiled portion and then crushing or flattening the coiled portion so as to deform the contacting parts into an interlocking engagement; but the invention is not limited to use in connection with any particular form of strap as it has general adaptability for the knotting of straps by a pressing or crushing operation.

The invention has for an object to provide such a tool which is hydraulically operated so as to insure uniformity and precision in the knotting or crushing operation at all times.

Another object consists in providing such a tool which is instantaneous in operation and requires no substantial physical effort on the part of the operator.

Another object consists in providing such a tool that includes means for maintaining a suitable temperature of the actuating fluid, e. g. oil.

Another object consists in providing such a tool that includes means for maintaining a given operating pressure in order to prevent either failure of operation or operation under excessive force.

Another object consists in providing such a tool in which there is normally a continuous flow of the operating fluid, and in which actuation of the knotting or crushing means takes place by interrupting said flow.

Another object consists in providing such a tool in which the main bulky or weighty portion may remain in a fixed position, while the knotting or crushing means is comparatively small and light and fitted to be operated at a distance from the main portion and in restricted spaces.

A further object consists in providing certain improvements in the form, construction, material and arrangement of the several parts whereby the above named and other objects may effectively be attained.

A practical embodiment of the invention is represented in the accompanying drawings, in 50 which

Fig. 1 represents a perspective view of the whole tool;

Fig. 2 represents a perspective view of the same looking in a direction opposite to Fig. 1;

Fig. 3 represents an enlarged detail section, partly in elevation, of the pump and associated parts, taken substantially in the plane of the line III—III of Fig. 4, looking in the direction of the arrows;

Fig. 4 represents a similar view taken substantially in the plane of the line IV—IV of Fig. 3, looking in the direction of the arrows;

Fig. 5 represents a horizontal detail section taken substantially in the plane of the line V—V of Fig. 3, looking in the direction of the arrows;

Fig. 6 represents a detail transverse section taken substantially in the plane of the line VI—VI of Fig. 3, looking in the direction of the arrows;

Fig. 7 represents a similar view taken substantially in the plane of the line VII—VII of Fig. 3, looking in the direction of the arrows;

Fig. 8 represents a diagrammatic view showing 20 the valve arrangement and flow of the operating fluid;

Fig. 9 represents a top plan view of the knotting or crushing head;

Fig. 10 represents a vertical section through 25 Fig. 9 with the parts shown out of operation;

Fig. 11 represents a similar view with the parts shown in operation; and

Fig. 12 represents a detail section taken substantially in the plane of the line XII—XII of 30 Fig. 10.

Generally speaking the tool comprises pumping mechanism and knotting or crushing mechanism, the two being in operative connection.

The pumping mechanism is chiefly represented 35 in Figs. 3 to 8, and includes an electric motor 1 that is mounted on a suitable base 2 and secured in position by cap screws or the like, two of which are shown and marked 3. The motor acquires its power through cable 4 from a suitable source of energy (not shown) in any well known or approved manner.

The motor shaft 5 has a fly wheel 6 fixed thereon, and a sprocket 7 is fast to the hub of the fly wheel. A sprocket chain 8 connects sprocket 7 with another, and larger, sprocket 9 that is fastened by screws 10 to the flange of a hub 11 that is keyed to a shaft 12 and held in position on the end of the shaft by a washer 13 and screw 14. A suitable housing or covering 15, which is screwed to a vertical wall 16, serves to encase the sprockets and chain.

As a result of the mechanism just described, it will be clear that operation of the motor 1 will drive the shaft 12 at a reduced speed as compared with that of the motor shaft 5.

The shaft 12 is rotatably mounted in ball bearings 17, 17 that are positioned against movement toward each other by a spacing tube 18 and by shoulders in a sleeve 19; while a packing gasket 20 and the crank head 21 that is keyed onto the inner end of shaft 12 hold the said bearings firmly against tube 18 and the shoulders in sleeve 19. The sleeve 19 is preferably formed integral with the vertical wall 16.

The crank head 21 carries an eccentrically mounted pin 22 which is set into a block 23 that is fitted to reciprocate vertically between piston heads 24, 25 for reciprocating the latter as shaft 12 and its crank head 21 rotate, for a purpose to be hereinafter described.

The parts just described are housed within a cylinder 26 that forms one branch of a T-shaped casting which is suitably supported on a base that is preferably cast integrally therewith and is denoted in general by 27, Fig. 1. The end of cylinder 26 is secured to vertical wall 16, as by screws, one of which is shown and marked 28.

The piston heads 24, 25 are formed in one piece, being connected by web 29, as is best shown in Fig. 5, and they carry long slender pistons 30, 31, which have their inner ends flanged and set in recesses formed in piston heads 24, 25, wherein they are rigidly secured by clamping plates 32, 33, which are fastened to piston heads 24, 25 by screws, two of which are marked 34, 35.

As already mentioned, cylinder 26 forms one branch of a T-shaped casting, and it will be observed, by particular reference to Fig. 3, that the remainder of the said casting consists of an elongated double cylinder denoted by 36, in which the piston heads 24, 25 reciprocate under the influence of shaft 12.

In the ends of double cylinder 36 are fitted plugs 38, 39, which are centrally bored to form chambers 40, 41, in which pistons 30, 31 have a close sliding fit in order to function therein by alternate compression and suction, as in the case of the usual combination of piston and cylinder.

Plugs 38, 39 are flanged and secured by screws to double cylinder 36, certain of the screws being shown and marked 42, 43. The said plugs are also provided with bores 44, 45 that house valves 46, 47 which find seats at the outer ends of the said bores and are yieldingly held on their seats by expansion coiled springs 48, 49 that abut plates 50, 51 which are secured by cap screws to plugs 38, 39, certain of the cap screws being shown and marked 52, 53, Fig. 5. It will be seen that the valves 46, 47 are so arranged as alternately to lift from their seats when pistons 30, 31 move so as to exert a suction in bores 44, 45, which latter are in communication with piston bores 40, 41, through passages 54, 55.

The plugs 38, 39 are provided with two more bores 56, 57, Fig. 5, in which are fitted valves 58, 59 that are held to seats formed at the inner ends of said bores by compression springs 60, 61 located in recesses 62, 63 which are in line with bores 56, 57 and are connected by a tube 64. Washers 65, 66, fitted at the ends of tube 64, serve as abutments for springs 60, 61. As a result of the arrangement just described, it will be clear that, when a compressive effect is exerted in bores 56, 57, the valves 58, 59 will lift from their seats and open communication from bore 56 to bore 57. Such compressive effect is alternately obtained by the reciprocation of pistons 30, 31 because the bores 40, 41, in which the pistons reciprocate, are connected with bores 56, 57 by the passages 54, 55.

The plug 39 is further provided with a recess

67 that is adapted to receive a valve casing 68 which has its inner end equipped with a conical valve tip 69 that finds a seat in an angular passage 70 formed in plug 39, which passage opens 5 into recesses 67 and 63 so as to establish communication therebetween. The wall of valve casing 68 has a port 71 formed therethrough, which 10 opens communication between recess 67 and a free space lying between plug 39 and the wall of double cylinder 36 adjacent to valve casing 68, which free space is denoted by 72 and serves as a bypass, as will be hereinafter described. The valve casing 68 is fitted to slide in recess 67 and is normally held in the position shown in Fig. 3, 15 in which valve tip 69 is seated to close passage 70 and the casing itself closes port 71, by an expansion spring 73 that abuts an adjustable screw plug 74 so as to provide for variation in the pressure exerted by spring 73 to keep valve tip 69 seated. The construction just described provides 20 a safety valve which is effective in the sequence of operations of the apparatus, as will be hereinafter described, to counteract excessive pressure built up during the crushing or knotting operation.

Plug 38 has an angular conduit 75 formed therein which communicates at one end with the recess 62 and opens at the other end through plate 50 for connection with a hose pipe 76 that 30 runs to the operative head of the apparatus, as will be hereinafter set forth. Another hose pipe 77 also communicates with the operating head and, to complete the circuit, is connected at 78, Fig. 2, with a radiator that is in communication 35 with the main body of the apparatus, as will be explained.

In order to insure proper alignment of the motor 1, the base 2, on which it is mounted, is 40 adjustably supported by bolts 79, 79 which are set in bosses 80, 80, formed on the double cylinder 36, and by cap screws 81, 81 that are threaded into the wall 16 and traverse slotted lugs 82, 82 depending from base 2.

Turning now to the operative head of the apparatus which includes the mechanism for knotting or crushing the wire strap, it comprises a hollow casing 83 that carries a reciprocating plunger 84 which has an enlarged piston head 85 that is provided with a gasket 86 held in position by a clamping washer 87 which is fixed to head 85 by screw 88. The upper part of the hollow casing 83 is sealed by a screw plug 89 which also has a gasket 90 fixed in position by washer 91 and screw 92.

55 The wall of casing 83 has an angular passage

93 formed therein which opens by port 94 into

the casing 83 intermediate the reciprocable

plunger 84 and the screw plug 89.

The angular passage 93 traverses a screw 60 threaded boss that is formed on casing 83 and mates with a coupling 95 that is threaded into the channel 96 of a neck piece 97 which, in turn, is connected by a coupling 98 with the hose pipe 76 that is in communication, as hereinabove described, with conduit 75 in plug 38.

Neck piece 97 has a cylindrical chamber 99 formed therein which is in open communication with the channel 96 by means of a port 100. One end of the said chamber is connected by a hollow screw plug 101 with hose pipe 77, and the other end is closed by a screw plug and gland which are together marked 102. A perforated valve piston 103 is fitted to slide in chamber 99 and is normally urged by spring 104 to the position shown in Fig. 10. The rod of piston 103,

which is marked 105, is pivotally connected at 106 to a valve operating lever that is, itself, pivoted at 107 on neck piece 97 and has a grip 108 for manual operation. Figures 10 and 11 show the valve mechanism just described in two positions, the normal position in Fig. 10 being such that the piston 103 permits communication between hose pipes 76 and 77, by way of port 100 and perforations 109 through piston 103, while the manually altered position, shown in Fig. 11, closes communication between the said hose pipes by moving piston 103 so as to cover port 100.

The lower end of plunger 84 carries a hardened crushing block 110 which is secured in position by a conventional form of dovetailed lock that is operated by screw 111. The said crushing block also carries a blade 112 and the block and cutter cooperate with a hardened anvil and cutting block 113 which latter is supported by a foot 114 that is cast integral with casing 83. Two expansion coil springs, one of which is shown and marked 115, are housed in plunger 84 and abut a shoulder 116 formed in casing 83 so as normally to urge the plunger into its upper or inoperative position illustrated in Fig. 10. The crushing and cutting, or operative position of the plunger, is shown in Fig. 11.

When in use the spaces in the three-part casting comprising the cylinder 26 and double cylinder 36 are filled with a fluid which can operate on a hydraulic principle; such, for instance, as light motor oil; and, to assure an abundant supply of the said fluid, a reservoir 117, Fig. 4, is set into the end of cylinder 26 opposite the sprocket 9 and is secured in position by screws 118. A filling cap 119 is provided in the top of the reservoir and, in order to prevent overheating of the oil, a radiator 120, which is preferably similar to an automobile radiator, is fixed to the reservoir as indicated at 121, 121. The upper part of the radiator is connected at 122 by a hose 123 with the reservoir 117 as indicated at 124. A fan 125, mounted on the end of motor shaft 5, opposite fly wheel 6, cooperates with radiator 120 for cooling purposes in a well understood manner.

From the foregoing description it will be apparent that the interiors of the cylinders 26 and 36, the reservoir 117, and the radiator 120 are all fitted to be in fluid communication with each other and with the operating head through hose pipes 76, 77 and 123, so that, when the operating head valve mechanism is in the normal position represented in Fig. 10, there is a complete circulation of the fluid through all said parts of the apparatus under the influence of the pumping action of pistons 30, 31.

Describing now the operation of the apparatus, it may be said that the parts just mentioned are normally filled with light motor oil or other suitable fluid and the motor is set in operation. The diagrammatic view shown in Fig. 8 of the drawings is helpful for an understanding of the operation and it may be said that the port therein shown as piercing the wall of double cylinder 36, which port is marked 126, is a diagrammatic representation of the connection of hose pipe 77 with radiator 120 at the point 78.

In Fig. 8, the pistons 30, 31 are shown in their extreme position at the right so that piston 30 is on its compression stroke and piston 31 on its suction stroke. The effect of piston 30 is indicated by the arrows, and it will be seen that it serves to drive the fluid out of chamber 40

through passage 54, into bore 56, past valve 58, into recess 62, and through conduit 75, hose pipe 76, channel 96, passage 93, and port 94 into casing 83 of the operating head. However, the fluid has no effect in the operating head with the valve mechanism of the latter in the normal position shown in Fig. 10, because it is also free to pass through port 100, chamber 99, perforated valve piston 109, and hose pipe 77, back to connection 78 on radiator 120, which connection, as previously mentioned, is represented at 126 in the diagrammatic showing of Fig. 8.

At the same time that the pumping effect just described is taking place under the compression effect of piston 30, the suction effect of piston 31 is drawing oil from the reservoir and cavities of the cylinders 26 and 36, as indicated by the arrows at the lower left part of Fig. 8, through bore 45, past valve 47, and through passage 55 into chamber 41.

When, now pistons 30 and 31 move to the left in Fig. 8, piston 31 acts on its compression stroke and forces the fluid out of chamber 41, through passage 55, into bore 57, past valve 59, through recess 63, through tube 64, through recess 62 and through conduit 75 into hose pipe 76. This action of the pistons, which opens valve 59, likewise closes valve 58, so as to require the fluid to move from recess 62 into conduit 75; and it also closes valve 47 so as to prevent any forcing of the fluid back into the spaces within cylinder 36.

Thus, under normal conditions, when the operating head is not in use, the pumping action of pistons 30 and 31 maintains a continuous flow of oil or other suitable fluid as just described without generating any substantial amount of hydraulic pressure.

When it is desired to actuate the operating head, it is only necessary for the operator to squeeze the grip 108 so as to move the connected valve mechanism into the position shown in Fig. 11, wherein valve piston 103 closes port 100. This will prevent return circulation of the fluid through hose pipe 77 and its connections, and will cause the pumping apparatus to build up hydraulic pressure in the hose pipe 76 and connected parts, which pressure will be exerted in casing 83 of the operating head upon plunger 84 so as to force the latter from the position shown in Fig. 10 to the crushing and cutting position shown in Fig. 11. This operation, including the generation of very high pressure, such, for instance, as twelve thousand pounds per square inch, takes place instantly upon actuation of the grip 108 and, as soon as the wire strap 127 has been deformed from the shape shown in Fig. 10 to that shown in Fig. 11, and the excess portion severed (all as is well understood in this art), the operator merely releases the grip 108, which permits spring 104 to move piston valve 103 to the position shown in Fig. 10. This releases the high pressure previously generated and reestablishes circulation between hose pipes 76 and 77 with their connected parts thereby removing pressure in casing 83 of the operating head; whereupon spring 115 returns plunger 84 to its elevated position, and the apparatus is in condition for operation upon another wire strap.

The high pressure generated by operating the hand grip 108 so as to cause piston valve 103 to close port 100 is regulated by safety valve 68 which is normally seated, as shown in Figs. 3 and 8, so as to close communication between angular passage 70 and recess 67. Should, however, the hydraulic pressure become sufficient to overcome

the power of spring 13 that controls safety valve 68, tip 69 of the latter will be unseated from passage 70 due to the pressure of fluid in the latter, whereupon the compression stroke of piston 31, instead of forcing the fluid only through tube 64 and parts leading thereto, will also force the fluid through passage 70, recess 67, port 71, bypass 72, back into the space within cylinder 36, as indicated by the arrow at the upper left hand part of Fig. 8, in which space there is very little pressure. Thus it will be clear that, by adjusting the tension of spring 13, a predetermined, uniform hydraulic pressure may be attained upon each use of the apparatus, and accidental excess pressure will be avoided.

In actual use, the apparatus is stationed adjacent the point at which the packages are to be strapped and the motor 1 is started so as to actuate the pistons 30, 31 of the pump, which actuation causes the fluid to circulate from conduit 75 of the pump through hose pipe 76, coupling 98, channel 96, port 100, chamber 99, perforated piston 103, and hose pipe 77 back to radiatori 120 at the connection 78, which last named connection is diagrammatically represented by 126 in Fig. 8. The details of the operations and parts by which the pistons 30, 31 generate and maintain this circulation have been hereinabove set forth at length and need not be repeated.

The operator now passes a strap around a package with its ends in overlapping position suitable for the crushing or tying step, and the operating head 83 is manually positioned so that its foot 114 passes under the overlapped ends of the strap 127, as illustrated in Fig. 10 of the drawings, with the crushing block 110 and blade 112 immediately thereabove. The grip 108 is then manually operated so as to move it from the position shown in Fig. 10 to that shown in Fig. 11 which causes piston 103 to close port 100 and stop the fluid circulation just described. This stoppage causes the pistons 30, 31 instantly to generate a very high hydraulic pressure, as hereinabove described, and to force the fluid powerfully through hose pipe 76, coupling 98, channel 96, coupling 95, passage 93, and port 94, into the operative head casing 83 above piston head 85, which latter is thereby forced downwardly so as to perform the crushing and severing operation upon the strap. The operator thereupon releases the grip 108 so that it is automatically returned by spring 104 to the position represented in Fig. 10 which reestablishes the substantially pressureless circulation of the fluid above described and simultaneously releases the pressure on piston head 85 so that it and the crushing block and blade carried thereby are returned by springs 115 to the elevated position shown in Fig. 10. With the parts in this position, the operative head is removed from the strapped package and is ready for use in connection with another package and strap, in which case the manner of use hereinabove described will be repeated.

From this brief recitation of the manner of practical use of the apparatus it will be seen that the pumping mechanism need not be moved and that it is normally idling so as to induce a substantially pressureless circulation of the hydraulic fluid through the parts of the apparatus other than the operating head. The said head is readily brought into cooperative position with respect to the package and strap because of its comparatively small size and light weight as well as the length and flexibility of the hose pipes 76, 77

and, by the simple operation of a hand lever, the substantially pressureless circulation is instantaneously changed to very powerful hydraulic pressure that is exerted within the operative head for the desired operation upon the strap. Release of said lever simultaneously releases said pressure and all parts are restored to their normal positions with the pump idling under substantially pressureless circulation.

It will be observed that this apparatus or tool is suited for uses in which only a small space is afforded for the tying or crushing operation, because the main body of the apparatus, including the pumping mechanism, may stand in any convenient place and the head or tool proper be carried in the hand of the operator to the point of its application to knot the strap, because of the length and flexibility of the hose pipes 76, 77 which, of course, may be of any desired length.

In view of the fact that the apparatus is principally designed for the strapping of material that is placed in a press before the strapping operation, there is no occasion for providing strap tensioning mechanism, because, when the strapped material such, for instance, as a pile of pulp board, is released from the press, it expands sufficiently to bring about the desired tightness or tension of the strap. Consequently, it is only necessary to place the strap around the

compressed material with its extremities in knotting position, and then bring the operating head of the tool into crushing relationship with the strap, as indicated in Figs. 10 and 11, whereupon the grip valve may be operated and the knot formed. It is evident that this may be done without moving either the main body of the apparatus or the material to be strapped, and that the small size of the operating head enables it to be used in places where the operation of a hand tool or the like would be either impossible or difficult.

It should be noted, however, that the tool is adapted for the strapping of materials that are not held in a press, since it will cooperate with any suitable form of tensioning mechanism by knotting straps that have been tensioned. Indeed, as mentioned at the outset, the tool is useful in connection with the knotting of any form of strap where the operation is performed by pressure, because it is only necessary to alter the form of the crushing block and anvil to suit the occasion whether it call for a mere crushing, or a bending, or a punching operation, or any combination of these.

Owing to the provision of means for adjusting the power of the safety valve spring, any reasonable desired hydraulic operating pressure may be generated, so that every strap will be knotted or crushed to the same uniform extent throughout the day and from day to day. This, of course, is not true in the case of mechanically operated tools that depend upon the strength and care exerted by the operator. Furthermore, the crushing or knotting is performed with great rapidity as compared with a hand operated tool; so that this improved apparatus or tool constitutes a marked step in advance from the point of view of effectiveness, uniformity, speed and convenience, not to mention other attributes inherent in the structure and mode of operation.

It will be understood that various changes may be resorted to in the form, construction and arrangement of the several parts without departing from the spirit and scope of my invention, and hence I do not intend to be limited to the details

herein shown and described, except as they may be included in the claims.

What I claim is:

1. A wire strapping tool for sealing and severing straps placed around packages comprising, a manually portable and operable head having sealing and severing mechanisms, a stationary means for generating hydraulic power to operate said mechanisms, a flexible conduit connecting the head and the stationary means to permit the head to be manually brought into operable relationship with a strap placed around a package and to provide for circulation of the hydraulic medium through the stationary means and the head, and a manually operable valve carried by the head for actuation by the operator after the head has been manually brought into operable relationship with a strap placed around a package to cause the hydraulic medium to activate the sealing and severing mechanisms.

2. A wire strapping tool for sealing and severing straps placed around packages comprising, a manually portable and operable head having sealing and severing mechanisms, a stationary means for generating hydraulic power to operate said mechanisms, a flexible conduit connecting the head and the stationary means to permit the head to be manually brought into operable relationship with a strap placed around a package and to provide for circulation of the hydraulic medium through the stationary means and the head, and a manually operable valve carried by the head for actuation by the operator after the head has been manually brought into operable relationship with a strap placed around a package to cause the hydraulic medium to activate the sealing and severing mechanisms, said head being relatively small and light with respect to said stationary means to enable the operator to seal and sever straps at points that would be inaccessible and impractical if the head included the power generating means.

3. A wire strapping tool for sealing and severing straps placed around packages comprising, a manually portable and operable head having sealing and severing mechanisms, a stationary means for generating hydraulic power to operate said mechanisms, a flexible conduit connecting the head and the stationary means to permit the head to be manually brought into operable relationship with a strap placed around a package and to provide for circulation of the hydraulic medium through the stationary means and the head, and a manually operable valve carried by the head for actuation by the operator after the head has been manually brought into operable relationship with a strap placed around a package to cause the hydraulic medium to activate the sealing and severing mechanisms, said flexible conduit being in open communica-

tion with the head and through the valve when the tool is not in operation to permit the hydraulic medium to circulate at sub-operating pressure, and the valve being arranged to close communication therethrough when it is manually actuated to obstruct the said circulation of the hydraulic medium and cause an instantaneous great increase in pressure for activating the sealing and severing mechanisms.

10 4. A wire strapping tool for sealing and severing straps placed around packages comprising, a manually portable and operable head having sealing and severing mechanisms, a stationary means for generating hydraulic power to operate said mechanisms, a flexible conduit connecting the head and the stationary means to permit the head to be manually brought into operable relationship with a strap placed around a package and to provide for circulation of the hydraulic medium through the stationary means and the head, a manually operable valve carried by the head for actuation by the operator after the head has been manually brought into operable relationship with a strap placed around a package to cause the hydraulic medium to activate the sealing and severing mechanisms, and means in open circulating communication with the head, the conduit and the power generating means for controlling the temperature of the hydraulic medium as it is circulated therethrough.

30 5. A wire strapping tool for sealing and severing straps placed around packages comprising, a manually portable and operable head having sealing and severing mechanisms, a stationary means for generating hydraulic power to operate said mechanisms, a flexible conduit connecting the head and the stationary means to permit the head to be manually brought into operable relationship with a strap placed around a package and to provide for circulation of the hydraulic medium through the stationary means and the head, a manually operable valve carried by the head for actuation by the operator after the head has been manually brought into operable relationship with a strap placed around a package to cause the hydraulic medium to activate the sealing and severing mechanisms, said flexible conduit being in open communication with the head and through the valve when the tool is not in operation to permit the hydraulic medium to circulate at sub-operating pressure, and the valve being arranged to close communication therethrough when it is manually actuated to obstruct the said circulation of the hydraulic medium and cause an instantaneous great increase in pressure for activating the sealing and severing mechanisms, and means for preventing a too great increase in said pressure.
